UNITED STATES PATENT OFFICE.

WALTER L. CHURCH, OF HOUSTON, TEXAS, ASSIGNOR OF ONE-HALF TO WILLIAM L. PEARCE, OF HOUSTON, TEXAS.

TUBING SLIP AND SPIDER.

Application filed July 24, 1928. Serial No. 124,594.

This invention relates to new and useful improvements in a tubing slip and spider.

One object of the invention is to provide a tubing slip formed of a plurality of tubing engaging jaws, hingedly connected together and specially adapted to handle pump tubing in a well bore.

Another object of the invention is to provide a tubing slip formed of a plurality of tubing engaging jaws hingedly connected together, the outside of the slip tapering downwardly to seat in a spider opening, and a novel type of handle whereby the slip may be handled as a unit.

15 A further feature of the invention is to provide a novel type of spider adapted to receive said slip.

With the above and other objects in view this invention has particular relation to certain novel features of construction, operation and arrangement of parts, an example of which is given in this specification and illustrated in the accompanying drawings, wherein:—

25 Figure 1 shows a side elevational view of the slip seated in the spider which is mounted on a casing head.

Figure 2 shows a plan view thereof.

Figure 3 shows an elevation of the slip.

35 Figure 4 shows a plan view thereof, and

Figure 5 shows a vertical sectional view of the slip, taken on the line 5—5 of Figure 4.

Referring now more particularly to the drawings, wherein like numerals of reference designate similar parts in each of the figures the numeral 1 designates a conventional casing head attached to the upper end of the well casing 2. Mounted on the 35 casing head there is a spider 3 having a downwardly converging seat 4. This spider is preferably formed of half sections whose abutting parts have the outturned marginal flanges 5, which abut and are secured together by the bolts 6. This spider has a relatively wide base 7, adapted to rest on the casing head and it may be anchored on the casing head by means of a cable or chain 8 attached to the spider base and wrapped around the casing or casing head 50 and said spider has a depending annular rib 9' which fits within the casing head to hold the spider against lateral movement on said head.

55 The slip, proper, is composed of a plural-

ity of jaws 9, 9, and 10, 10, there being preferably four of said jaws. The end jaws 10, 10, are free, that is they are not connected together, but these end jaws are hinged to the adjacent intermediate jaws 9, 9, and said intermediate jaws are hinged together.

These jaws 9 are hinged together by means of connecting link 11 and the jaws 10, 10, are connected to the adjacent jaws 9 by means of similar connecting links 12, 12. The ends of these respective links are inserted into the deep slots as 13, 13, and 14, 14, of the corresponding jaws 9 and 10 and pins as 15 and 16 are passed downwardly through said jaws and through the corresponding ends of the respective links and their lower ends are threaded into the jaws, said pins forming pintles on which the jaws swing and their upper ends being flush with the upper ends of the corresponding jaws so as to provide a smooth upper surface for the slip. The outer corners of the jaws are rounded off, as at 17 and 18, so that they will freely open without binding, one against the other. The links 11 and 12 serve also to hold said jaws in substantially transverse alignment so that they will be maintained in position at all times to simultaneously engage the tubing.

The jaws are arcuate in horizontal cross sectional contour, and have their inner surfaces toothed to engage the tubing 19 with the outer surfaces tapering downwardly to conform to the shape of a fit within the seat 4 and wedge in between said tubing and spider so as to grip and hold the pump tubing suspended in the casing.

An inverted U-shaped bail 20 is provided, the free ends of whose side arms 21 are inwardly turned and fitted through the eyes 25 of eye bolts 22, 22, which in turn are attached to opposing links 12, 12. These arms are held against detachment from the eye bolts 22 by the cotter keys 23 and their other ends are inwardly turned and fitted loosely into the corresponding ends of the tubular grip 24 and retained therein by the cross pins 25, 25, thus forming a flexible handle for the slip. By this bail, or handle, the slips may be readily handled as a unit 100 and the jaws thereof permitted to swing freely open or closed. When the tubing is elevated the slip may be readily lifted out of the spider and the jaws swung open to release them from the tubing and when it is 110

desired to suspend the tubing from the spider the slip may be seated in the spider with its jaws closed around the tubing and said jaws will wedge between the tubing and the spider seat and grip and hold the tubing suspended in the bore.

What I claim is:—

1. A tubing slip comprising a plurality of jaws the facing sides of adjacent jaws having slots, links connecting said jaws whose ends fit into the corresponding slots a bail whose ends are connected to opposing links between the corresponding jaws and pintles carried by the jaws and working in bearings in the corresponding ends of said links.
2. A tubing slip including a plurality of arcuate wedge shaped jaws, links connecting said jaws together, the jaws at one side of the slip being disconnected from each other to permit the slip to be disposed around, or removed from a tubing in a well bore, a pair of eyebolts connected to two of said links and a bail having overturned ends which have bearings in the eyes of said bolts.
3. The combination with a spider having a downwardly tapering seat, of a slip tapered to conform to the contour of and adapted to fit in said seat, said slip including a plurality of jaws whose facing sides have slots forming bearings, links connecting said jaws together and whose ends work in said bearings and a means through which said slip may be handled as a unit said means comprising a bail, and means connected to opposing links and located between the corresponding jaws and to which the respective ends of the bail are connected.
4. A tubing slip comprising a plurality of jaws hinged together, a handle formed with a grip member and side arms, said arms being flexibly connected at one of their ends to said grip member and at their other ends to the slip.
5. A tubing slip comprising a plurality of jaws hinged together, means for handling the slip as a unit, said means comprising a handle formed of side arms and a grip mem-

ber, said arms being pivotally connected to the slit at one of their ends and flexibly connected at their other ends to said grip member.

6. A tubing slip comprising a plurality of jaws, links connecting the adjacent jaws together except at one open side of the slip, eye bolts connected to opposing links, means for handling the slip as a unit, said means comprising a handle having side arms and a grip, said arms being overturned at one of their ends and fitted through the eyes of said eye bolts and being overturned at their other ends and fitted loosely into the respective ends of said grip and means preventing the detachment of said arms from said grip.

7. A tubing slip having a smooth upper surface and including a plurality of jaws, connecting links intermediate said jaws and having a pivotal connection with the corresponding jaws and connecting the jaws together except at one open side of the slip the facing sides of the connected jaws having opposing slots forming bearings in which the respective ends of the corresponding links work, a bail and means connecting the respective ends of said bail to opposing links.

8. A tubing slip including a plurality of jaws, connecting links intermediate said jaws except at one open side of the slip, the facing sides of the jaws connected by said links and having opposing slots which extend to the outer surfaces of said jaws and which form bearings for the respective ends of the corresponding links, pins extending through said jaws and through the ends of the links and forming means for connecting the links to the respective jaws, a bail and means connected to the respective ends of the bail and also to opposing links and connecting said bail to said links, said connecting means working between the corresponding jaws.

In testimony whereof I have signed my name to this specification.

WALTER L. CHURCH,
